United States Patent Office.

JOHN NORTH, OF NEW YORK, N. Y., ASSIGNOR TO HIMSELF AND WILLIAM T. HOLT, OF SAME PLACE.

Letters Patent No. 91,765, dated June 22, 1869.

IMPROVED ROCK-DRILLING APPARATUS

The Schedule referred to in these Letters Patent and making part of the same.

To all whom it may concern:

Be it known that I, JOHN NORTH, of the city, county, and State of New York, have invented a new and useful Machine for Drilling in Rock and in the Earth; and I do hereby declare that the following is a full, clear, and exact description of the construction and operation of the same reference being had to the annexed drawings, making a part of this specification, in which—

Figure 1 is a vertical perspective view of said machine;

Figure 2 is a plan of the same;

Figure 3 is a horizontal section thereof;

Figure 4 is a detached view of the adjustable frictional feed-gears.

The chief aim or purpose of my invention is to furnish suitable machinery for successfully operating a certain diamond-pointed rock-drill, patented by Rudolphe Leschot, in 1863, but it may be used as well for operating any kind of rotating drill or tool for boring in rocks or in the earth.

My invention consists in a combination of mechanical devices for the rotating, feeding, controlling, and adjusting of the drill, so that the same may be conveniently operated without loss of power or time, and made to drill in any direction without changing the position of the machine.

To enable others skilled in the art to make and use my invention, I will proceed to describe its construction and operation, with reference to the drawings.

In constructing my drilling-machine, I make the upright shafts A A, fig. 1, fastened together at each end by the cross-bars c c, having extension-screws, B B B, which are used to set the machine firmly against the sides of the drift or tunnel in which it is operated.

To this upright frame, I attach a movable drill-frame, D, which slides upon the same, and is held fast at any desired point by the clamp H and nut g, fig. 2, which is screwed against the clamp H.

Inside of this drill-frame D, I secure the circular disk of the drill-head E, figs. 1 and 3, by means of the hollow shaft J, which is connected therewith, and forms a part of the same.

This hollow shaft passes through the respective centres of the frame D, clamp H, and nut g, and is held fast by the nut K, fig. 3.

The outer periphery of the circular plate of this drill-head E is slightly bevelled, to fit the adjustable frame D, causing a friction when the nut K is screwed tight.

The drill-head is thus held fast at any desired point, with its attached drill-rod inclined to any angle required for drilling, and the drill is pointed in any direction, to suit the operator, by releasing the nut K, which secures the drill-head, as described.

The drill-head E is supplied with two boxes, attached to the same, for the support of the nut and sleeve-gear, through which the screw-shaft R is worked.

The feed-shaft S is supported on the opposite side, parallel to the screw-shaft R, and is held secure by the same caps, V V, which hold the sleeve-gears and screw-shaft.

The crank P is fastened to the pinion O, and revolves on a stud made fast to the adjustable arm W.

The pinion O gears into gear N, which is screwed fast to the shaft L, passing through the hollow shaft of the drill-head.

This shaft L, which is the driving-shaft, has a bevel-gear attached to its front end, gearing into the lower teeth of the sleeve-gear, which is feathered into the slot of the screw-shaft, as shown in fig. 1, whereby a rotary motion is imparted to the screw-shaft and drill.

By releasing the nut K, the position of the crank P and pinion O may be changed to suit the operator, and worked either at top of gear N, as shown, fig. 1, or at bottom of same.

The drill-rod or tube 3', of any desirable length, passes through the hollow screw-shaft R, and is held fast to the same at any desired point by means of the set-screws and chock, 2 2.

This drill-rod has a thread cut on its lower end, of a pitch opposite to that of the thread upon the screw-shaft, to which the boring-head or bit, with diamond teeth, is screwed fast.

The gear Y, which is the upper portion of the sleeve-gear, figs. 1 and 2, gearing into gear X, gives motion to the feed-shaft S, which revolves in an opposite direction to the screw-shaft.

At the lower end of the feed-shaft S is attached the feed-gear A², which gears into gear B², made fast to the screw-nut 5.

Feed-gear A² has one or more teeth more than gear B², causing the nut to run faster than the screw, and giving a positive feeding or forward motion to the screw-shaft and drill, called a differential feed.

In my experience in drilling stone with diamonds, I have found that in order to drill hard and soft stone with the same machine, a self-adjusting feed is desirable, as the diamonds are otherwise liable to be loosened in their settings, by drilling through soft rock into hard rock at a high rate of speed. I therefore use a self-adjusting feed, in combination with the differential feed above described.

I make the feed-gear A² a frictional one, (see fig. 4,) and thereby produce a combined differential and frictional feed.

The feed-shaft S is made tapering at its lower end, A', fig. 4, and the feed-gear A² is made to fit the same, and backed by a washer or collar, B', and is held in position and adjusted by the nut 2.

The feed-gear being adjusted sufficiently tight to

drive the screw-nut when drilling soft rock, on coming to hard rock, the frictional gear will slip, and thus the pressure; when the drill-bit will be adjusted at a uniform rate.

All danger of injuring or loosening the diamonds, by changes in the hardness of the rock, is thus obviated.

The gear X, attached to the upper end of the feed-shaft 8, is so arranged as to be slipped out of gear when the screw has run down to any desired depth, causing the screw to run up its length by the same motion of the engine or crank, and driving-shaft L, which carried it down, but with a velocity far greater.

When the gear X is slipped back in place, the screw feeds down again, as before. This gear is easily adjustable on the feed-shaft 8, to which it is fastened by the motion of the finger.

The sliding steady-guide t is adjustable to any position, and is used to steady the drill-rod or boring-bar, as the same passes into the rock, in order to prevent any shake or tremor of the same in boring.

I am aware that other machines have been invented for operating drills of various kinds, and I hereby expressly disclaim all previous inventions of like nature with my own, particularly that of A. Haupt, of May 2, 1865; but

What I claim as my invention, and desire to secure by Letters Patent, is—

1. The drill-frame D, adjustable at any point upon the upright frame A A, by means of the nut g, when said frame is used in combination with the swivel-head E, substantially as and for the purposes set forth.

2. The swivel drill-head E, supporting a sleeve-gear and drill-rod, when used in combination with a drill-frame, whether adjustable or otherwise, and secured thereto by the hollow shaft I and the nut K, substantially as and for the purposes set forth.

3. The hollow screw-shaft R, when used in combination with the swivel drill-head, sleeve-gear, and feed-nut, or their equivalents, substantially as and for the purposes described.

4. The release-gear X, when used in combination with the driving and sleeve-gear, substantially as and for the purposes described.

5. The adjustable steady-guide, when used in combination with the drill-head, screw-shaft, and boring-bar, substantially as and for the purposes specified.

6. The straight and continuous driving-shaft L, passing through the crank-arm W, clamp H, hollow shaft J, nuts g and K, and drill-head E, substantially as and for the purposes specified.

JOHN NORTH.
